(57) **CLAIM**

The ornamental design for a creeper body, as shown and described.

DESCRIPTION

FIG. 1 is a side view of the creeper body of this invention, with the sides of the creeper body being mirror images of each other;

FIG. 2 is a bottom plan view of the creeper body of this invention;

FIG. 3 is an end view of the creeper body of this invention looking at the foot end of the creeper body; and,

FIG. 4 is an end view of the creeper body of this invention looking at the head end of the creeper body.

The top of the creeper body is not part of the claimed design. The broken line disclosure is for illustrative purposes only and forms no part of the claimed design.
